UNITED STATES PATENT OFFICE.

ELBERT R. HOBBS, OF BUHL, IDAHO.

ROTARY VALVE.

1,137,758.

Specification of Letters Patent. Patented May 4, 1915.

Application filed June 7, 1913. Serial No. 772,404.

To all whom it may concern:

Be it known that I, ELBERT R. HOBBS, a citizen of the United States, residing at Buhl, in the county of Twin Falls and State 5 of Idaho, have invented certain new and useful Improvements in Rotary Valves, of which the following is a specification, reference being had therein to the accompanying drawing.

10 My invention relates to valve gears for fluid engines and more particularly to rotary valves.

An object of my invention is to provide a 15 rotating valve that will work equally well with both low and high speed engines and will perform the function of a double valve with greater efficiency and simplicity of operation than has heretofore been accomplished with the usual reciprocating double 20 valve.

Another object of the invention is to provide a double acting valve that can be operated from the engine through a simple means of transmission instead of the two 25 eccentric necessary to the operation of the usual reciprocating double valve.

A further object is to reduce the number 30 of sliding surfaces and relatively moving parts in a valve of the above type and further to so construct the parts as to compensate for variations in certain wearing factors such as velocity, rubbing surface, etc.

Other objects of the invention will appear 35 from the following specification and accompanying drawings and will be particularly pointed out in the claims.

Referring to the drawings: Figure 1 is a 40 top plan view of a preferred form of valve seat, Fig. 2 is a top plan view of a valve plate adapted to coöperate with the valve seat of Fig. 1, Fig. 3 is a top plan view of a cap piece or cut-off valve for coöperation 45 with the valve plate of Fig. 2, Figs. 1^a, 2^a and 3^a are modified forms of coöperating members, Fig. 4 is a cross-sectional view 50 taken on the line x—x of Fig. 2, and Fig. 5 is an assembled view partly in section and showing the relation of the several parts and a form of transmission that may be used.

55 Referring to Figs. 1, 2, 3 and 4, 1 is the valve seat or base plate in which the cylinder ports of a steam or other fluid engine terminate at the apertures 4 and 5. A hole 6 is provided in the base plate to admit concentric shafts for operating the valve mem-

bers 2 and 3 superposed in the order named upon the base plate 1. The radial apertures 7 to 18 inclusive, in the valve plate 2 register with the apertures 4 and 5 in the base plate 1, so that as the plate 2 is revolved upon the 60 plate 1 by means of a suitable hollow shaft passing loosely through plate 1 and keyed in the shaft hole 19 of plate 2, said perforations will be successively brought over the apertures 4 and 5. Arc shaped recesses 65 20 and 21 are provided on the under part of the plate 2 and are adapted to pass over the outer part of the apertures 4 and 5. The recesses 20 and 21 each pass around the plate 2, near the circumference, so far as to be just 70 out of connection with the apertures 4 and 5 when the plates 1 and 2 are positioned in the angular relation shown. The recesses 20 and 21 communicate respectively, with perforations 7 and 18. The cap-piece or cut- 75 off valve member 3 is formed with a recess 22 and a chamber 23 each adapted to communicate with the perforations 7 to 18 in plate 2. The recess 22 and the lower opening of the chamber 23 are so proportioned 80 and arranged as to be out of connection with the perforations 7—18 of the plate 2 when the members 2 and 3 are in the angular position shown. The member 3 is adapted to be revolved upon the member 2 by means of 85 a suitable shaft passing loosely through the shaft of plate 2 and fixedly connected to the member 3. It will be seen that when the several parts 1, 2 and 3 are superposed in the order named and in the angular position indicated, there will be no communication between any of the spaces of the different 90 parts. However, if the cap-piece 3 is rotated in a clockwise direction, the recess 22 will be brought into communication with one or several of the perforations 13 to 18 95 according to the amount of rotation, and the chamber 23 will be brought into communication with the same number of perforations in the group 7 to 12, and with the recess 100 20 via the perforation 7. The recess 22 is in constant communication with a source of power through any suitable means such as a steam chest, to be later described, and the chamber 23 is in constant communication 105 with an exhaust pipe through the hollow spindle 24. If, while in the relative positions just described, both members 2 and 3 are rotated together counter clockwise, upon the base plate 1, the recess 22 will be brought 110

into communication first with the aperture 4 and later with aperture 5, via one or several of the perforations 13 to 18 and during a portion of a complete revolution proportionate to the number of perforations 13 to 18 with which recess 22 is in communication; while the chamber 23 will be brought into communication first with the aperture 5 and later with aperture 4 via perforation 7 and recess 20, and for a half of a revolution each.

In order to minimize the necessary amount of relative movement of the members 2 and 3 for bringing the recess 22 and chamber 23 into communication with any number of perforations, 13 to 18 or 7 to 12, said perforations are arranged in close groups at the upper surface of the member 2 and diverge from each other and widen toward the lower surface as shown in the sectional view of Fig. 4.

In Figs. 1^a, 2^a and 3^a, the members 1^a, 2^a and 3^a are modified forms of, and correspond in function to the members 1, 2 and 3, respectively. In this form of valve the hollow spindle for exhaust is done away with by the provision of a stationary exhaust duct (not shown) terminating in apertures 25 in the base plate or valve seat 1^a. The member 2^a, in addition to the perforations 26 to 38 and recesses 39 and 40, corresponding in function to the perforations and recesses in the member 2, is provided with perforations 41 and 42 which pass over the apertures 43 and 44 in the valve seat 1^a, and a group of perforations 43 which pass over the apertures 25 in the valve seat 1^a when the member 2^a is rotated upon the member 1^a. The cap-piece 3^a is formed with a recess 46 and an arc shaped perforation 47 which corresponds in function to the recess 22 of the member 3. The member 3^a is also provided with a bridging recess 48 adapted, when the members 3^a and 2^a are rotated one upon the other, to bridge the perforation 41 or 42 with the group of inner perforations 43. When the members 1^a, 2^a and 3^a are mounted one upon the other in the order named and in the angular position shown, the apertures 43 and 44 are disconnected from the recess 46 or perforation 47 by the body portion of the intermediate member 2^a. Also, the apertures 25 are disconnected from the apertures 41 and 42 by the body portion of the member 2^a. If the cap-piece 3^a is now rotated clockwise in relation to the intermediate member 2^a the recess 46 will be brought into communication with one or several of the apertures 32 to 38, according to the amount of rotation, and the bridging recess 48 will be brought into communication with the perforation 41 and one of the apertures 43. If the members 2^a and 3^a are now rotated, in fixed relation to each other and in a clockwise direction, upon the valve seat 1^a the aperture 43 will be brought into

communication with the recess 46 via one or several of the perforations 32 to 38 during a portion of the revolution proportionate to the number of said perforations with which recess 46 is in communication, while the aperture 44 is brought into communication with the exhaust apertures 25, via the bridging recess 48 and apertures 41 and 43, during a half of a revolution. At each half revolution, the relation between the apertures 43 and 44 and the recesses 46 and 48 is transposed.

In Fig. 5 I have shown the form of valve made up of the elements shown in Figs. 1 to 4, assembled within the steam chest 49 upon the cylinder 50 of a steam engine. In this illustration the valve seat 1 is shown integral with the base of the steam chest 49, and the ducts 51 and 52 are shown connecting the ports of the cylinder with the apertures 4 and 5, respectively, of the valve seat. Motion is transmitted from the fly wheel of the engine through the gear train comprising the groups of gears 53—54 and 55 to 60, connected through the shaft 61. The gear 55 is rotated at the same rate as the fly wheel through the shaft 61 and gears 53—54. The gear 55 meshes with the gear 60 which is fixed to the hollow spindle 62 which in turn is keyed to the valve member 2. 55 95 also meshes with 56 which together with the gear 57 is fixed to the collar 63 rotatably mounted on the spindle 62. Motion is transmitted from 57 through 58 to 59 thereby causing 59 to rotate in the same direction 100 as the gear 60. 59 is keyed to the shaft 65 which at its upper end is fixed to the cap member 3 by means of a squared head 66 and nut 67. As all meshing gears are of the same size the rate of rotation of the valve 105 members 2 and 3 is the same as that of the fly wheel of the engine. The idler gear 58 is journaled on the shaft 71 and adapted to rotate about the axes of gears 57 and 59 by means of a collar 69, which is journaled on 110 the spindle 62 and carries the shaft 71. The rotation of the gear 58 about the axes of gears 57 and 59 is accomplished by means of a handle 70, held in position by a pawl 72 adapted to engage perforations in the 115 bracket 64 fixed to the cylinder or other stationary part of the engine. The purpose of the particular arrangement of gears 55 to 59 is to enable the valve members 2 and 3 to be rotatably adjusted in relation to each other 120 whether or not the engine is running. Assuming that gear 55 is stationary and the idler 58 is rotated about the spindle 62 $\frac{1}{4}$ revolution, it will rotate about its axis $\frac{1}{4}$ revolution carrying the gear 59 around $\frac{1}{4}$ revolution at the same time advancing it another $\frac{1}{4}$ revolution by transmitting its rotation thereto. Thus the valve member 3 will be rotated $\frac{1}{2}$ revolution while the valve member 2 remains stationary. It will thus 130

be seen that this same relative movement of the valve members will take place whenever the idler 58 is rotated about the spindle 62, and whether or not the engine is running. 5 It is by this means of adjustment that the relative movement of the valve members 2 and 3 as set forth in the description of Figs. 1 to 4, is accomplished.

The special arrangement of differential 10 gears here shown for the adjustment of the movable valve members is particularly adapted to such adjustments requiring a wide angular movement, as only $\frac{1}{4}$ rotation of the idler 58 about the spindles is required 15 to effect a 180° adjustment of the valve members. Other means may be used for adjusting the relative positions of the valve members 2 and 3, such as the well known spirally-slotted sleeve and pin connection 20 between the concentric spindles 62 and 63. The hollow spindles 62 and 24 pass out of the steam chest through suitable stuffing boxes 68 and 68^a, respectively. Steam is conducted to the steam chest through the 25 pipe 73 and valve 74.

The operation is as follows: Assuming that the valve adjusting arm 70 has been set to bring the recess 22 into communication with the perforation 13, and the exhaust chamber 23 into communication with the recess 20 via perforation 7, and that steam, under pressure, is admitted into the steam chest 49, the steam will pass into the head end of the cylinder via recess 22, perforation 13, aperture 4 and duct 52. This causes the piston of the engine to be driven forward turning the fly wheel, in a well known manner, which motion of the fly wheel is transmitted to the valve gear in a manner as before described. As the piston moves forward, the crank end of the cylinder is exhausted via duct 51, aperture 5, channel 20, perforation 7, exhaust chamber 23 and hollow spindle 24 to a condenser 45 or to atmosphere. The admission of steam into the head end of the cylinder will continue until the perforation 13 passes wholly out of communication with the aperture 4 while the crank end will continue to exhaust, through the channel above traced, 50 until the piston reaches the end of its stroke, and the fly wheel has made $\frac{1}{2}$ a revolution, whereupon the recess 22 moves out of communication with the aperture 5 and the relation between the apertures 4 and 5 and the 55 rotating valve members becomes reversed. This reversal causes steam to pass into the crank end of the cylinder via the spaces 22, 13, 5 and 51 and permits the head end to exhaust via spaces 52, 4, 20, 7, 23 and 24, thus 60 causing a reversed operation of the piston which completes the rotation of the fly wheel. The operation above described covers a complete cycle of operation of parts.

The portion of the cycle during which steam 65 is admitted may be varied by adjustment of the valve members as set forth in the description of Figs. 1 to 4.

In order to counteract unequal wear between the members 1 and 2 due to the increased velocity near the periphery, these members are made with gradual increasing hardness from the center toward the periphery. Another means employed for compensating for the increased wearing rate at 70 the periphery of the members 1 and 2, is to cut away portions of the rubbing surfaces where the wearing rate is low to bring it up to the maximum and thereby produce 75 uniform wear. 80

In practice I contemplate using either one or both of these means for effecting uniform wear in the same valve gear. For example, conditions may arise where it is required to have the valve seat 1 integral with some 85 massive part of the engine which would make the first method, that of variation in hardness, difficult and therefore would require the application of the latter method, that of varying the amount of wearing surface. 90

In order to compensate for unequal wear due to the fact that those portions of the valve seat which contact with solid portions of the rotating member will wear at a 95 greater rate than those portions which contact with the perforated or recessed portions of the rotating member, the solid portions may be varied in diameter or portions of the valve seat recessed or cut away, so as to distribute the wear equally. 100

Various other arrangements of the different parts may be made without departing from the spirit and scope of the invention. For example, the steam chest and valve 105 mechanism may be so positioned with relation to the other parts that the shaft 63 may be formed integral with the shaft 61 or the shaft of the fly wheel and thus either reduce or do away with the intermediate transmission. 110

Having thus described my invention, what I desire to secure by Letters Patent is:

1. Valve mechanism comprising a valve seat having apertures therein, a movable valve plate having passages therein adapted to be brought into communication with said apertures in the valve seat, and means for connecting a source of operating fluid with one or more of said passages. 120

2. Valve mechanism comprising a valve seat having apertures therein, a movable valve plate having passages therein adapted to be brought into communication with said apertures in the valve seat, and means operating in fixed relation to said valve plate 125 for connecting a source of operating fluid with one or more of said passages.

3. Valve mechanism comprising a valve seat having apertures therein, a valve plate having a plurality of groups of passages isolated from each other and movable in relation to said valve seat to bring each of said passages into communication with the apertures in the valve seat during a determinate portion of the movement of said plate and means for simultaneously connecting one or 10 more of said passages of one group with a source of operating fluid and one or more of the other group of passages to exhaust.

4. Valve mechanism comprising a valve seat having apertures therein, a valve plate 15 having a plurality of groups of isolated passages therein and adapted to be rotated upon said valve seat to bring said groups of passages into communication with said apertures alternately, and an adjustable valve 20 member having inlet and exhaust recesses and adjustable in relation to the valve plate to bring one of said recesses into communication with one or more passages in one of said groups and to bring the other of said 25 recesses into communication with one or more passages in another of said groups.

5. Valve mechanism comprising a valve seat having apertures therein, a rotatable valve plate having a plurality of isolated 30 passages therein, rotatable fluid conveying means adjustable in relation to said valve plate to connect a portion of said passages with a source of operating fluid and another portion with an exhaust, and means for rotating said valve plate and said fluid conveying means in fixed relation to each other to bring said passages into communication with said apertures successively.

6. Valve mechanism comprising a valve 40 seat having apertures therein, a rotatable valve plate having a plurality of isolated passages therein, rotatable fluid conveying means adjustable in relation to said valve plate to connect a portion of said passages 45 with a source of operating fluid and another portion with an exhaust, means for rotating said valve plate and said fluid conveying means in fixed relation to each other to bring said passages into communication with said apertures successively, and means for adjusting the fixed relation between said valve 50 plate and fluid conveying means.

7. Valve mechanism comprising a valve seat having apertures therein, a rotatable valve plate therefor for controlling the admission and emission of operating fluid through said apertures, a rotatable regulating device for the valve plate adjustable in relation thereto to vary the time of emission 55 and means for rotating said valve plate and regulating device synchronously, together with means for adjusting said regulating 60

device in relation to the valve plate during rotation.

8. Valve mechanism comprising a rotary 65 cut-off valve, a rotary timing device associated with said cut-off valve and adapted upon variation in angular relation to the cut-off valve to vary the time of the cut-off, means for rotating said cut-off valve and timing device in fixed relation to each other and to the movements of the engine and means for varying the angular relation between said cut-off valve and timing device.

9. Valve mechanism comprising a valve 75 seat having apertures therein, a valve plate having a plurality of groups of isolated passages adapted to be rotated upon said seat to bring said groups of passages into communication with said apertures alternately, 80 and an adjustable member having inlet and exhaust passages, a portion of said member farthest from the valve open to the atmosphere or a condenser and affording a discharge passage for the exhaust.

10. Valve mechanism comprising a valve seat having apertures therein, a valve plate having a plurality of groups of isolated 90 passages adapted to be rotated upon said seat to bring said groups of passages into communication with said apertures alternately, and an adjustable member having inlet and exhaust passages, a portion of said member at one end farthest from the valve open to a source of operating fluid and furnishing 95 a conducting passage for the same.

11. In a rotary valve mechanism, a movable part compensated for wear by having its contacting surfaces variably hardened in direct proportion to their relative rate of 100 movement.

12. Valve mechanism comprising a valve seat having apertures therein, and a valve plate having isolated passages therein and adapted to be rotated upon said valve seat 105 to bring the passages into alternate communication with the apertures, said isolated passages diverging from each other and from the center in passing through the valve.

13. Valve mechanism comprising a valve 110 seat having apertures therein, and a valve plate having passages therethrough and adapted to be moved upon said valve seat to bring the passages in varied communication with the apertures, said passages expanding or increasing in size in passing through the valve, being larger on the face of the valve that is in contact with the seat.

In testimony whereof I affix my signature in presence of two witnesses.
